UNITED STATES PATENT OFFICE.

HAROLD C. SUCKERT, OF NEW YORK, N. Y.

VACUUM FUEL-FEEDING SYSTEM FOR GASOLINE-ENGINES.

1,274,810.

Specification of Letters Patent.

Patented Aug. 6, 1918.

Application filed December 23, 1915. Serial No. 68,331.

To all whom it may concern:

Be it known that I, HAROLD C. SUCKERT, a citizen of the United States, and resident of the borough of Manhattan, city, county, and State of New York, have invented certain new and useful Improvements in Vacuum Fuel-Feeding Systems for Gasoline-Engines, of which the following is a specification.

10 In vacuum fuel-feeding systems heretofore used, the gasoline or other liquid fuel is drawn into a tank or chamber until a pre-determined quantity is accumulated, whereupon devices are operated to discharge the 16 accumulated gasoline into another receptacle from which it flows to the carbureter. The great objection to feeding systems of this character is that there is no means of assuring a proper supply in the receptacle 20 from which the gasoline flows to the carbureter. It frequently happens, with feeding systems of this type, that the supply for the carbureter is exhausted before the proper quantity has been drawn into the first or 26 receiving receptacle. When this occurs the engine, of course, stops for lack of fuel and must be cranked or otherwise operated until the receiving tank is supplied with the proper amount of gasoline to cause it to 30 again empty its contents into the carbureter supplying tank.

It has been proposed to use two complete and independent feeding systems the object being to arrange said systems to operate to 35 discharge gasoline from the receiving tank into the carbureter supply tank or receptacle alternately. In this double arrangement of apparatus there is no assurance that the receiving tanks will operate alternately for 40 the reason that they operate absolutely independently, neither one of the feeding systems controlling the other in order to secure the sequence of operation.

It is one of the principal objects of this 45 invention to provide a single fuel-feeding unit or system in which a plurality of receiving tanks or receptacles will be provided, said receiving receptacles to be filled or charged with gasoline in succession and 50 then discharged into the carbureter supply tank as rapidly as needed and only when needed.

Another object of the invention is to provide a single unit feeding apparatus in which 55 a plurality of receiving tanks will be used, one of said tanks forming a reserve tank.

Another object of the invention is to provide a single unit fuel-feeding system in which a plurality of receiving tanks will operate in connection with a single carbureter supply tank, the receiving tanks being automatically brought into position to receive their charges of gasoline and then automatically moved into position to discharge their contents as required, into the 60 carbureter supply tank.

A further object of the invention is to provide a single unit fuel-feeding apparatus, in which a plurality of receiving tanks are employed in connection with a single carbureter supply tank, means being provided whereby when one of said receiving tanks is discharging into the carbureter supply tank another of said receiving tanks is connected to the suction apparatus by which 70 gasoline is drawn from the supply tank, whereby when one of said receiving tanks is discharging its contents another of said tanks is being charged.

In the drawings, Figure 1 is a side elevation showing the apparatus in position for use;

Fig. 2 a vertical sectional view of the carbureter supply tank showing two of the inner receiving tanks in sectional view;

Fig. 3 a vertical central sectional view on the line III—III of Fig. 2;

Fig. 4 a transverse sectional view on the line IV—IV of Fig. 2;

Fig. 5 an elevation of the inner face of 90 one of the journals which support the rotating receiving tanks; and

Fig. 6 a detail sectional view thereof on the line VI—VI of Fig. 5.

Referring to the various parts by numerals 1 designates a gasoline engine, 2 the intake manifold thereof, 3 the carbureter and 4 the fuel storage tank which is located below the carbureter. Mounted in any suitable position above the carbureter is a casing or tank 5 which serves as a carbureter supply tank, the bottom of said tank being connected to the carbureter by means of a pipe 6. A gasoline supply pipe 7 extends from the supply tank 4 to the intake of the tank 5; and an exhaust pipe 8 extends from the tank 5 to the intake manifold 2 of the engine. The tank 5 is preferably circular in form for convenience in manufacture and is rigidly supported in any suitable manner.

In the sides of the tank 5 at opposite points and axially in line with each other

are rigidly mounted conical journals 9 and 10. These journals are hollow and to the journal 9 is connected the gasoline supply pipe 7; and to the journal 10 is connected the 5 exhaust or suction pipe 8. These journals extend into the tank and mounted to rotate thereon is a valve device 11, the ends of said device being bored axially to receive the conical bearings 9 and 10. Mounted on the 10 valve device within the tank 5 are a plurality of receiving tanks or receptacles 12. As shown in the drawings there are three of these tanks radially mounted on the valve device equal distances apart. One of said 15 tanks is directly below the axial line of the valve device in its discharging position. The tank which is in its receiving position inclines upwardly and to the right, as viewed in Fig. 2 of the drawings, whereby when it 20 is fully charged with gasoline it will move downwardly, thereby lifting the tank which is discharging its contents. The other tank, which is empty, inclines upwardly and to the left, as viewed in Fig. 2, this tank being 25 moved around into its filling position when the filled tank moves downwardly to its discharging position. The valve device is provided with an exhaust port 13 and a gasoline supply port 14 communicating with each receiving tank. These ports extend from the receiving tanks to the conically bored ends of the valve device. The exhaust port is connected at its inner end to a pipe 15 which extends close to that corner of its receiving 30 tank which is uppermost when the said receiving tank is in its upper receiving position, so that the outer end of this exhaust pipe will be at all times above the liquid therein, as shown clearly in Fig. 2. The 35 journal 9 is provided with an inlet port 16 and the journal 10 is provided with an exhaust port 17, said ports being so positioned that they register with the corresponding ports 14 and 13, respectively, of a receiving 40 tank when said tank is in its upper receiving position. When any one of the receiving tanks is in its upper receiving position the inlet and exhaust ports of the other tanks are closed by the solid portions of the conical journals 9 and 10, said journals forming 45 valves to close said ports.

Each receiving tank is provided with a discharge aperture 18 in its side, near its outer end. To close this aperture when the tank is in its receiving position a valve arm 19 is provided, carrying a valve 20 adapted to drop into the aperture 18. This valve arm is pivoted at the outer end of the receiving receptacle and its free end is 50 weighted as at 21. As shown in Fig. 2, the discharge aperture and the gravity valve are so placed that they will be on the upper side of the receptacle near its upper, outer end, when the receptacle is in its receiving position.

When, however, the receptacle is in its lower or discharging position the valve arm will swing outwardly or away from the tank, thereby opening the discharge aperture and permitting the fuel supply to flow into the carburetor supply tank. To limit the 55 outward swinging movement of the valve carrying lever, said lever is provided with a stop finger 22 which is adapted to engage the wall of the receiving tank.

To hold the valve device in proper position to maintain one of the receiving receptacles in its upper receiving position with the receiving and exhaust ports of said receptacle in register with the supply and exhaust ports of the journals 9 and 10, a spring-pressed friction locking ball 23 is mounted in the valve device in position to engage a recess or depression 24 in the flange of the journal 10. The tension of the spring 25 is sufficient to hold the latch ball 23 in its depression until the receiving tank has been supplied with a predetermined quantity of gasoline. The weight of this predetermined quantity will overcome the friction of the latch ball and thereby rotate the valve device and the connected receiving tanks. This rotation will be only sufficient to carry the latch ball from the depression 24 into a deeper depression 26. This partial rotation of the latch device will be sufficient to close the supply and exhaust ports in the journals 9 and 10. When the latch ball is seated in the depression 26 all of the inlet and supply ports for the receiving receptacles will be closed. The lowermost receiving receptacle will continue to discharge its supply of gasoline and the weight of the gasoline in the lowermost receptacle, together with the friction of the latch ball in the depression 26, will be sufficient to hold the receptacle 100 and the valve device against rotation. When, however, the lowermost receptacle has discharged its gasoline the weight of the full tank will be sufficient to release the latch device from the depression 26 and cause said 105 receptacle to move to its lower position. This movement of the full tank to its lowermost or discharging position will bring the next tank in sequence to its receiving position and connect its supply and exhaust ports 110 to the corresponding ports in the valve device, so that this tank will be receiving its supply while the full tank is discharging its contents into the carburetor supply tank. The valve device is provided with a spring 115 ball latch for each receiving tank so that when a tank reaches its upper receiving position its latch will snap into the recess 24.

Extending from the exhaust passage of the journal 10 is a relief port 27 which port 120 is closed by one of the latch balls 23 whenever a receiving tank is in its receiving position. When, however, a receiving tank

has been filled and has moved to its intermediate or reserve position with the latch in the deeper holding recess 26, the relief port is open and thereafter the suction is 5 through said relief port until the receiving tank next to be filled is brought to its upper receiving position. When the suction is through relief port 27, the air is drawn from the interior of the vessel 5, this vessel 10 being provided with an air inlet 28 at its top. The exhaust ports from the receiving tanks, and the relief port 27 are of the same size or capacity, so that the amount of air taken into the intake manifold through the 15 exhaust pipe 8 is the same at all times. This permits the adjustment of the carburetor for a uniform air supply or leak so that the mixture supplied to the engine will not vary. This is desirable and overcomes one 20 of the serious defects in vacuum fuel feeding systems for gasoline engines. By reason of this uniform air supply or leak the exhaust ports may be made considerably larger than in the old style feeding systems 25 thereby insuring a quick filling of the receiving tanks and an adequate supply of gasoline at all times for the carburetor supply tank.

When the filled tank has been moved to 30 its reserve position, the port 16 connecting with the pipe 7 is sealed, that is to say, its communication with pipe 7 is closed by reason of the fact that the valve device has made a partial rotation and port 16 has 35 been carried around out of register with said pipe 7. The result of this is that the vacuum in pipe 7 and in the main fuel tank is maintained so that said pipe 7 will be at all times fully charged with gasoline. This 40 is of great advantage in apparatus of this type, for the reason that in the next charging operation it will not be necessary to again build up the vacuum in pipe 7, resulting in a very considerable saving in time 45 for the charging operation. When the engine is moving slowly with the throttle fully opened, as in ascending steep grades, the suction in the manifold, and consequently through pipe 8, is very much reduced. Under 50 these conditions the ordinary vacuum fuel feeding apparatus fails, the suction being insufficient to move a full supply of gasoline from the fuel tank into the feeding apparatus. A feeding apparatus constructed as described herein will respond very promptly, and a full charge of gasoline will be drawn into one of the receiving tanks quickly, even upon a greatly reduced suction. This results not only from sealing 55 the pipe 7 and maintaining the vacuum therein, but by reason of the provision of a plurality of small receiving tanks arranged to discharge in succession into the main carburetor supply tank.

From the foregoing it is manifest that I provide a single unit feeding system, comprising a series of receiving tanks which are connected in succession to the exhaust apparatus and to the main fuel supply, one of said tanks being connected up to receive 70 its charges or supply whenever a fully charged tank is discharging its contents into the carburetor supply tank. The result of this arrangement is that one receiving tank will be receiving its charge or supply while another is discharging its contents into the carburetor supply tank. It is also manifest that I provide means whereby when one of the receiving tanks is completely charged it is disconnected from the fuel supply tank 80 and the exhausting means, and its contents held in reserve until the tank which is discharging its contents into the carburetor supply tank is empty, or substantially so, the reserve tank then discharging its contents into the carburetor supply tank and an empty receiving tank being connected to the gasoline supply and the exhaust. 85

In a fuel feeding system constructed as herein described, the valve device is automatically operated to connect the main gasoline supply tank and the exhausting means to a plurality of receiving tanks in succession, which tanks are in succession discharged into the carburetor supply tank as the gasoline is required therein to supply the carburetor. It is also clear that the weight of the accumulated gasoline in the receiving tanks serves as the means for operating the valve device, and also as means 100 to move the fully charged receiving tank into its intermediate or reserve position, and then into its discharging position when the previously filled tank is empty, or substantially so. 105

The discharging port 18 of the receiving tanks serves as a means for regulating the height of the gasoline in the carburetor supply tank. It is manifest that when the gasoline in the latter tank rises above the said discharge opening in the receiving tank said opening will be sealed and the further discharge of gasoline prevented until the level of the liquid in the carburetor tank has been sufficiently lowered to uncover at least a portion of said discharge port. By this means the weight of the gasoline contained within the lowermost or discharging receiving tank will serve as a means to assist the latch device in holding the reserve tank in its intermediate position. It is manifest that if all of the contents of the discharging tank were permitted to pass into the carburetor supply tank at once, the reserve tank would then move to its discharging position, resulting in an over-supply of gasoline in the carburetor supply tank. It is important, therefore, that the discharge aperture of the re- 110 115 120 125

ceiving tanks be in such position that the height of liquid in the carbureter supply tank will be maintained at the proper point.

What I claim is:

5. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 75
6. In an apparatus of the class set forth, the combination of an engine, a main supply tank, a carbureter, and means connected to the intake of the engine for automatically supplying gasoline to the carbureter, said means embodying a receiving vessel, a port connecting the interior of said vessel with the intake of the engine, another port leading from the intake to the atmosphere, and automatic means for closing the port leading to the interior of the vessel when the vessel is filled and connecting the other port to the atmosphere, said two ports being of the same capacity so that the amount of air taken into the intake of the engine is at all times approximately the same. 95
7. In an apparatus of the class set forth, the combination with a main supply tank and an internal combustion engine provided with a carbureter, of a means connected to the intake manifold of the engine for automatically supplying gasoline from said tank to said carbureter, said means embodying a carbureter-supply-tank, a rotatable structure provided with a series of receiving tanks each of which is adapted to dip into the liquid in the carbureter-supply-tank, means being provided whereby each tank in succession automatically feeds its contents into said carbureter-supply-tank by the change of level of the liquid in said carbureter-supply-tank, and devices whereby one of the upper receiving tanks will be filling while the dipped tank is discharging and also whereby the dipped tank after it has discharged its contents will be elevated by the weight of the liquid in the previously-filled elevated tank. 100
8. A fuel feeding system comprising a main supply, a carbureter supply tank, an exhausting means, a series of receiving tanks, means for connecting said receiving tanks independently and succession with the gasoline supply and the exhausting means, and means for successively and automatically disconnecting the filled tanks from the exhausting means and permitting them to discharge by gravity into the carbureter supply tank said means connecting the empty tanks in succession with the exhausting means and the main supply. 110
9. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 115
10. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 120
11. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 125
12. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 130
13. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 135
14. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 140
15. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 145
16. A fuel feeding system comprising a single carbureter supply tank, a series of receiving tanks, a valve device having a gasoline supply port and an exhaust port, and a relief port connected to said exhaust port, means for automatically connecting one of said receiving tanks to the exhaust port and supply port of the valve device, and another of said receiving tanks to the carbureter supply tank to empty its contents therein by gravity, and means for closing the relief port when one of the receiving tanks is connected to the supply and exhaust port of the valve device. 150

9. A fuel feeding system comprising a main supply, a carbureter supply tank, an exhausting means, a series of receiving tanks, means for connecting said receiving tanks independently and in succession with the gasolene supply and the exhausting means, means for successively and automatically disconnecting the filled tanks from the exhausting means and permitting them to discharge by gravity into the carbureter supply tank said means connecting the empty tanks in succession with the exhausting means and the main supply, means for holding one filled tank out of discharging and receiving position while one tank is discharging its contents into the carbureter supply tank.
10. A fuel feeding system comprising a main supply, a carbureter supply tank, an

exhausting means, a series of receiving tanks, 20 means for connecting said receiving tanks independently and in succession with the gasolene supply and the exhausting means, means for successively and automatically disconnecting the filled tanks from the exhausting means and permitting them to discharge by gravity into the carbureter supply tank said means connecting the empty tanks in succession with the exhausting means and the main supply, means for holding one filled 30 tank out of discharging and receiving position while one tank is discharging its contents into the carbureter supply tank and sealing communication with the main supply to maintain the vacuum therein. 35

In testimony whereof I hereunto affix my signature.

HAROLD C. SUCKERT.
